UNITED STATES PATENT OFFICE.

WILLIAM A. McGINNIS, OF DETROIT, MICHIGAN.

GARMENT HANGER.

Application filed May 19, 1921. Serial No. 470,786.

To all whom it may concern:

Be it known that I, WILLIAM A. McGINNIS, a citizen of the United States of America, residing at Detroit, in the county of Wayne and State of Michigan, have invented certain new and useful Improvements in Garment Hangers, of which the following is a specification, reference being had therein to the accompanying drawings.

10 This invention relates to garment hangers, and has special reference to that class of hangers composed of pivoted foldable members with spreader arms therebetween, said spreader arms maintaining the foldable members extended so that a coat or similar garment may be suspended from said members and with the spreader arms in an active position, a pair of trousers may be swung over said spreader arms.

20 The primary object of my invention is to provide an all metallic garment hanger of the above class which can be finished to present a neat and attractive appearance and be comparatively light in weight, the metal entering into the construction of the hanger permitting, of rounded smooth surfaces being imparted to the movable members of the hanger so that garment suspended from the foldable member will not be 30 torn or injured.

A further object of my invention is to provide novel pivotal connections for foldable hanger members, said pivotal connections permitting of the ends of the 35 foldable members being readily shaped so that a rivet, pivot pin or the like may be easily installed to articulate the movable members.

The above and other objects may be attained by the construction shown in the drawings, wherein

Figure 1 is a front elevation of the metallic garment hanger, partly broken away and partly in section;

45 Fig. 2 is a plan of the garment hanger;

Fig. 3 is an enlarged detail sectional view taken on the line III—III of Fig. 1;

Fig. 4 is an enlarged cross sectional view taken on the line IV—IV of Fig. 1;

50 Fig. 5 is a front elevation of a portion of the garment hanger partly folded;

Fig. 6 is a front elevation of a modified form of garment hanger;

55 Fig. 7 is a perspective view of a portion of the garment hanger shown in Fig. 6, with the foldable members collapsed;

Fig. 8 is a perspective view of a pivotal connection that may be established between foldable members;

Fig. 9 is a perspective view of one of the 60 members shown in Fig. 8;

Fig. 10 is a cross sectional view taken on the line X—X of Fig. 6, and

Fig. 11 is a cross sectional view taken on the line XI—XI of Fig. 1. 65

Considering Figs. 1 to 5 inclusive, and Fig. 11, the garment hanger comprises sheet metal inverted channel shaped members 1 and 2 having outer rounded and closed ends 3. The member 2 is of greater length than 70 the member 1 so that the inner end of the member 2 may overlie the inner end of the member 1, and the inner end of the member 2 is rounded and closed, as at 4 so that its walls will be flush with the walls of the 75 member 1 and thus finish off the top or apex of the garment hanger when in an extended operative position.

The side walls of the member 2, adjacent the inner end thereof, are provided with 80 inset parallel apertured lugs 5 and the side walls of the member 1 are adapted to extend on to the lugs 5 so that the side walls of the member 1 may be connected to the lugs 5 by a transverse rivet or pin 6, as best shown in 85 Fig. 3. One or both of the walls of the member 2 may be apertured, as at 7, to receive the inner end of a hook 8 by which the garment hanger may be suspended from a suitable support. 90

Pivots mounted in the outer inclosed ends of the members 1 and 2 by transversely disposed rivets or pins 9, are the outer ends of inverted channel shaped spreader arms 10 and 11, the spreader arm 10 having its inner 95 end offset and extending to the inner end of the spreader arm 11, so that said arms may be pivotally connected by a transverse rivet or pin 12. The inner ends of the spreader arms 10 and 11 have pressed out matched interengaging portions 13 which will hold the spreader arms 10 and 11 in longitudinal alignment and prevent accidental collapse of said spreader arms when the members 1 and 2 are extended. 100

With the members 1 and 2 hollow the spreader arms 10 and 11 can recede into said members and be enclosed thereby when said members are folded into parallelism, at which time the hook 8 may be swung on to 110 said members so that the garment hanger can be conveniently packed in a valise. I

attach considerable importance to this simple form of hanger as the parts thereof can be readily stamped from sheet metal and bent to form.

- 5 In Figs. 6, 7 and 10 a more expensive construction is disclosed wherein the foldable members 14 and 15 have the same type of spreader arms, but the pivotal connections between the members 14 and 15 is somewhat more elaborate. In the first place, the inner end of the member 14 is enlarged so as to form a head 16 when contacting with the inner end of the member 15, and the ends of said members are inturned so as to 10 provide end walls 17 and 18 which will abut when the members 14 and 15 are extended. As shown in Fig. 7, the side walls of the short member 15 are bent inwardly and then outwardly to afford parallel apertured lugs 19 and 20 extending between said lugs are the inwardly bent contacting apertured lugs 20 of the head 16, the lugs 19 and 20 being pivotally connected by a rivet 21 or somewhat similar pivotal means.
- 15 25 Instead of the short member 15 being provided with the apertured lugs 19, said member may have its end wall inbent to provide a central transverse trough or member 22 into which the lugs 20 of the head 16 may extend and be held by a transverse rivet 23. This pivotal connection is shown in Fig. 8 and in some instances the corners of the short member 15 may be cut away, as at 24, so that a short rivet may be employed for retaining the lugs 20 within the trough 22.
- 30 35 With suitable dies and formers the various pieces of the garment hanger can be

easily produced, dipped or otherwise finished to present a neat appearance, and then assembled as an article that may be advantageously used by travelers and those requiring a foldable garment hanger. 40

What I claim is:—

1. A garment hanger comprising a long hollow member, a short hollow member, said long member having inturned walls providing an end wall and outstanding apertured contacting lugs, said short hollow member having inturned walls providing end walls, one disposed at an angle to the other, one of 45 said angular end walls adapted to abut the end wall of the long member, outstanding apertured parallel lugs carried by the other angular end wall of said short member and between which parallel lugs extend the lugs 50 of the long member, means pivotally connecting the lugs together, spreader arms connecting the outer ends of said members and adapted to be enclosed by said members, and a hook carried by one of said members. 55 60

2. A garment hanger as called for in claim 1, wherein the parallel apertured lugs of the short member have straight edges in the plane of the angular end wall of the short member and straight edges in the 65 plane of the longitudinal straight edges of said short member.

In testimony whereof I affix my signature in presence of two witnesses.

WILLIAM A. McGINNIS.
